UNITED STATES PATENT OFFICE

2,003,635

BEAM HANGER

Charles M. Markham, Detroit, Mich.

Application June 23, 1932, Serial No. 618,976

1 Claim. (Cl. 25—131.5)

My invention relates to hangers for use in hanging concrete forms or molds from supporting beams.

It is an object of the present invention to provide a hanger for concrete forms which may be supported entirely from the girder or beam around which the concrete is to be molded and which will do away entirely with extraneous supports of any kind.

10 It is another object of the invention to provide an improved cross member by supporting the soffit sections of the mold and to provide improved suspending means for this cross member by which it may be readily fastened in position 15 without the use of any special tools whatsoever.

Still another object of the invention is to provide an improved form of connecting means for the ends of the suspending means which will readily adapt the same to be used with various 20 sizes of beams and girders without altering either the suspension means or the soffit supporting cross member in any way.

Other important objects and advantages of the invention will become apparent during the 25 course of the following detailed description of the invention when read in conjunction with the accompanying drawing which forms a part of this specification and in which,

Figure 1 is a vertical sectional view of an I-beam showing my improved mold hanger applied thereto;

Figure 2 is an enlarged plan view of the means for joining the ends of the suspending strips;

Figure 3 is a perspective view of one end of 35 the mold supporting cross member;

Figure 4 is a sectional view taken on the line 4—4 of Figure 3, and

Figure 5 is a partial perspective view of one 40 of the strip end fittings before the strip is secured thereto.

Referring now more specifically to the details 45 of the drawing, wherein like numerals refer to like parts throughout the same, 10 indicates a beam or girder, in this case shown as an I-beam and from which is suspended a form or mold including a soffit board 11 which is spaced from and centered with respect to the base flange 12 of the beam 10 by means of combined spacer and gauge strips 13, said strips being rabbeted 50 along their upper and inner edges to form a seat for the edges of the flange 12.

The soffit board 11 and other mold parts are supported upon a cross member 14 which extends transversely of and is suspended from the beam 10 by means of sheet metal strips 15 and

16 which are joined together over the top flange 17 of the beam 10 in a manner to be hereinafter described. The cross member 14 is composed of a pair of angle bars 18 disposed in parallel spaced relation with the angles thereof disposed in opposite directions. The angle bars 18 are held in spaced relation by means of rods 19 which are formed with reduced ends 20 fitted in openings 21 in the vertical flanges 22 of said angle bars.

10 The strips 15 and 16 each carry a seat member 23 adjacent their lower ends which extends transversely beneath and upon which the cross member 14 is supported, said strips extending down between the angles 18 and secured to the 15 seat members adjacent the center thereof in the manner hereafter described.

The seat members 23 are each formed of a strip 20 of sheet metal having the ends thereof bent back upon opposite sides of the middle portion as at 47 and 48 to form a laminated member of triple thickness. The strips 15 and 16 are each secured to the seats in the same manner so that a description of one will suffice for both. The lower 25 end of the strip 16 is brought down between the end 48 and the center portion of the seat 23 and then bent upwardly between said portion and the end 47 so as to embrace the center and the free end is then bent down over the top edge of the end 47. Thus the ends are securely attached to 30 the seat members without requiring the use of any kind of fastening means whatever. It will also be noted that this method of attaching the strips to the seat members also permits ready adjustment of the length of the strips to exactly the 35 length desired.

The strip from which the seat members 23 are formed is provided with widened portions at the ends and also at intermediate points where the bends occur so that when the strip is folded to 40 produce the finished seat, upstanding lugs or stops 49 will be formed at the ends of the seat to prevent lateral movement of the cross member off the ends of the seats.

The upper ends of the strips 15 and 16 are secured to connector members 24 and 25 respectively which normally rest on the top flange of the I-beam 10, said member 24 being in the form of a bifurcated plate and the member 25 being formed as a substantially flat plate having a 45 tongue 26 formed on one side adapted to extend between the furcations 27 and 28 of the member 24. The free ends of the furcations 27 and 28 and of the tongue 26 are bent under upon themselves 50 to provide opposed flanges 29 and 30 respectively 55

for engagement by a wedge member 31 which when driven into the position shown in Figure 2 will draw the members 24 and 25 together to take up any slack in the strips 15 and 16 and thereby firmly clamp the cross member 14 in position.

Each of the members 24 and 25 are formed with oppositely disposed ears 32-33 and 34-35 respectively which serve to aid in securing the ends of the strips 15 and 16 to said members. The end 10 of the strip 15 is brought up under the member 24 through the bight portion thereof and bent back upon itself as at 36 whereupon the ear 33 is bent inwardly over this portion 36. The end is then reversed and the ear 32 bent inwardly over the 15 reversed portion 37, the extreme end 38 then being bent back over the ear 32. The body portion of the member 25 is struck up to form an eye or loop 39 through which the end of the strip 16 is drawn, the end being then secured in much the same 20 manner as the end of the strip 15. It will be noted that the point of the wedge 31 is upturned as at 31^a to prevent it from being entirely withdrawn.

In order to provide for securing the sides of the 25 concrete form in position, slideable clamping members 40 are mounted upon the cross member 14, each of said clamping members comprising a base 41, and upstanding opposed flanges 42, the edges of the base 41 being inturned under the horizontal 30 flanges of the angles 18 as at 43 to slidably secure the clamps thereto.

The horizontal flanges of the angles 18 are each formed with elongated slots 44, the slots in one flange being staggered with respect to those 35 in the other flange, and a wedge 45 carried on the end of a chain 46 secured to the clamps 40 is adapted to be driven into a selected one of said slots to force the clamps 40 tightly into position to clamp the sides of the form in operative position.

In operation, with the seats 23 secured in the proper position on the strips 15 and 16 for the size beam to which the form is to be secured and with the strip 15 secured to the connector mem-

ber 24 and with the wedge 31 retracted to the limit allowed by the upturned end 31^a, the end of the strip 16 is drawn through the eye 39 and pulled tight by hand and then secured by the ears 34 and 35 as has been previously described. The wedge 31 is then driven home to draw the strips 15 and 16 much tighter than would be possible by hand and to secure the member 14 rigidly in position. The clamps 40 are then slid up against the sides of the mold and the wedges 46 secured in the proper slots to maintain them securely in tightened position. The tip of the wedge 31 may be bent back upon itself as indicated in dotted lines to insure that the parts will not become loosened through accident.

It will thus be seen that I have provided an extremely simple and efficient mold clamp and hanger which may be quickly secured in operative position without the use of any special tools and with very little effort.

While a preferred embodiment of the invention has been shown and described, it will be distinctly understood that various modifications in the details of construction and operation may be resorted to without departing from the spirit of the invention within the scope of the appended claim.

Having thus described my invention, what I claim as new and desire to secure by Letters Patent is:

In a beam hanger for concrete forms, a form supporting cross member, strips for suspending said cross member from a beam, seat members carried by the lower ends of said strips and upon which said cross member is adapted to rest, said seat members each comprising a one piece laminated sheet metal member, said strips having the lower ends thereof looped under an intermediate lamination and confined by adjacent laminations of said members, said strips extending over said beam from opposite sides thereof, and means for connecting the ends of said strips together.

CHARLES M. MARKHAM.
